United States Patent Office

Des. 186,903
Patented Dec. 22, 1959

186,903

CHAIN LINK OR SIMILAR ARTICLE

William F. Hess, Providence, R.I.

Application December 9, 1958, Serial No. 53,708

Term of patent 14 years

(Cl. D45—4)

FIG. 2

FIG. 3

FIG. 4

FIG. 5

FIG. 1

Fig. 1 is a perspective view of a chain link embodying my new design;

Fig. 2 is a fragmentary top plan view of three chain links joined, on a reduced scale;

Fig. 3 is a side elevational view thereof;

Fig. 4 is an end view; and

Fig. 5 is a bottom plan view thereof.

I claim:

The ornamental design for a chain link or similar article, substantially as shown.
